[57] CLAIM

The ornamental design for a resistor sorting machine, as
shown and described.

DESCRIPTION

FIG. 1 is a perspective view taken from above and one
side of resistor sorting machine showing my new de-
sign;

FIG. 2 is a front elevation thereof;

FIG. 3 is a right side elevation thereof;

FIG. 4 is a rear elevation thereof;

FIG. 5 is a left side elevation thereof;

FIG. 6 is a top plan view thereof; and

FIG. 7 is a bottom plan view thereof.
